EMORY P. WALKER, OF BELCHERTOWN, MASSACHUSETTS.

Letters Patent No. 77,135, dated April 21, 1868.

IMPROVEMENT IN BUTTER-WORKER.

The Schedule referred to in these Letters Patent and making part of the same.

TO ALL WHOM IT MAY CONCERN:

Be it known that I, EMORY P. WALKER, of Belchertown, in the county of Hampshire, and in the State of Massachusetts, have invented certain new and useful Improvements in Butter-Workers; and do hereby declare that the following is a full, clear, and exact description thereof, reference being had to the accompanying drawings, and the letters of reference marked thereon.

In the annexed drawings, making a part of this specification, A represents the bottom of a rectangular box or frame, having a hole, x , through it, near the front end; B B, the sides of the same, provided with slots $a a$, extending nearly the whole length of them; C, one end of the frame, the top being cut away as low as the lower side of the slots $a a$, and D D the front-end pieces, placed diagonally, so as to form an apex at their intersection, in the middle of the bottom A, and just in front of the hole x . The whole is supported by suitable legs, $c c c c$, the two in front sufficiently shorter than the others, to give the desired pitch or inclination to the frame.

$d d$ represent arms or holders, framed together by the handle c at one end, and the guide-bar g at the other, which extends through the sides $d d$, and slide backward and forward in the slots $a a$. A roller, h , is adjusted into the arms $d d$, and works on the face of the bottom, A; to press and thoroughly work buttermilk, water, or other liquid out of butter, or to mix different grades and colors of butter, making the mixture a homogeneous mass, and of uniform color.

The pieces D D are designed to hold the butter from being pushed over the end of the bottom, A, and to conduct the water or other liquid to the hole x .

N represents a paddle to handle the butter with, so that it is unnecessary to touch the butter at all with the hands.

I am fully aware that the general construction and operation of the within-described device are not new.

Having thus fully described my invention, what I claim as new, and desire to secure by Letters Patent, is—

The diagonal flanges D D, placed at the mouth or front end of the bottom, A, of the box, with a hole, x , as described, the various parts being constructed and operating as specified.

In testimony that I claim the foregoing, I have hereunto set my hand, this 5th day of December, 1867.

EMORY P. WALKER.
